UNITED STATES PATENT OFFICE.

THEODORE SCHMAUSER, OF ALLEGHENY, PENNSYLVANIA.

THERAPEUTIC GALVANIC APPARATUS.

SPECIFICATION forming part of Letters Patent No. 423,959, dated March 25, 1890.

Application filed December 3, 1889. Serial No. 332,365. (No model.)

To all whom it may concern:

Be it known that I, THEODORE SCHMAUSER, a citizen of the United States, residing at Allegheny, in the county of Allegheny and 5 State of Pennsylvania, have invented certain new and useful Improvements in Therapeutic Galvanic Apparatus, of which the following is a specification.

This invention pertains to therapeutic galvanic apparatus, its object being the production of an apparatus which will be convenient of manipulation, compact of form and construction, and efficient in operation.

The present invention covers improvements 15 upon Letters Patent issued to me Nos. 246,036 and 246,037, dated August 23, 1881, and No. 312,660, dated February 24, 1885. The points of improvement relate to the manner of supporting the electrodes of the cells, to the construction of the zinc electrode, to the combination, with a therapeutic galvanic apparatus, of a milliammeter of novel construction, whereby, in connection with a rheostat, I am able to ascertain and administer the proper 25 strength of current to a construction whereby the whole apparatus may be quickly and easily put into a conveniently-portable condition, and to the means for raising and lowering the battery-cells for the purpose of immersing 30 the electrodes in the electrolytic fluid.

The following drawings are attached to and form a part of this specification:

Figure 1 represents a general perspective view of the apparatus in working condition. 35 Figs. 2 and 3 represent perspective views of the apparatus, seen in two parts to render it easily portable. Fig. 3^a is a detail view of a hinge used in connection with this apparatus. Fig. 4 is a side elevation of the apparatus with a portion of the case and cover broken away. Fig. 5 is a vertical section through a portion of one side of the case. Figs. 6 and 7 are vertical sections, taken at right angles to each other, of the milliammeter 40 used in connection with this apparatus. Fig. 8 is a detail perspective view of a couple of elements, showing the manner of supporting the same. Fig. 8^a is a section through the device which supports the elements. Fig. 50 9 is an elevation of the zinc element used in my battery before the insulating material is applied to one of its sides. Fig. 10 is a plan of a supplemental bottom for one of the parts of the apparatus when it is divided. Fig. 11 is a central section of the same, and Fig. 12 55 is a diagram of the circuits.

Referring, first, to the manner of supporting the elements or electrodes of the battery, E, Fig. 1, represents a supporting-plate which is placed flush with the top edges of the case A 60 when the cover A² is thrown back. This plate is made of either hard rubber or a similar insulating material and is provided with a number of rows—in this instance four—of slots e, each one of which is adapted to receive a 65 screw d, supporting two battery-elements D D'. The screw enters a slot and is secured in place by clamping it between or against its top and bottom sides. This screw is secured in a block d' in such a manner that it cannot be 70 removed therefrom. In Fig. 8^a the block is shown in section. It is formed with a chamber d⁵ in its lower side and a threaded perforation d⁶, of smaller diameter, extending therefrom through the top of the block. The screw 75 works in the threaded perforation and is fitted with a nut d⁷, which occupies the chamber and prevents the removal of the screw. The block d is of hard rubber or other suitable insulating material. To the top of this block there 80 is connected a metallic clip d². It is secured in place by projecting pins d³. The ends of this clip extend beyond the sides of the block and are bent downward at right angles, leaving a wide and a narrow space, respectively, 85 between the sides of the block and the bent portions of the clip. In this space thus formed are placed the electrodes D D'—one of carbon and the other of zinc—and they are held when in position by an inwardly-projecting lip in 90 the clip which engages with a groove in the head of the electrode. The electrode is inserted in place by bringing its groove into line with the lip and sliding it laterally into place, as shown in Fig. 8. The elements of the battery being coupled in series, one of the elements D, when in working condition, is located in one cell, while the other element is located in the next adjoining cell, the two being in 95 electrical connection through the metallic clip 100 d². Then the couple is secured to the supporting-plate E. The projecting pins d³ fit into

small cavities d^1 , (shown in dotted lines in Fig. 8,) and thus prevent any rotation or displacement of the couple. It will thus be seen that I have provided a simple means of supporting the couples which will admit of their ready removal and replacement, either from the supporting-plate E or the block d' and clip d^2 .

In one of my previous patents above referred to I have described a battery element consisting of a thin zinc plate, one side of which is coated with a layer of insulating material. I have found in practice that unless special means are provided this coating of insulation will sometimes crack and fall off, principally at the edges of the plate, and to prevent this I propose to bend the two side edges and the bottom edge over at an angle of about thirty degrees, thus forming a kind of trough, and place the insulated coating in the trough, so that its edges are thoroughly protected.

So far as known to me I am not aware of an instance in which a milliammeter has been placed permanently in connection with the casing of a portable galvanic battery. Milliammeters are of late sometimes used in connection with such apparatus; but they are always separate and cumbersome structures. My idea is to provide a milliammeter of diminutive size and to locate the same within the battery-casing and to provide suitable connections and switches for throwing it into circuit at any time. Milliammeters are used in connection with medical galvanic batteries for the purpose of measuring the amount of current administered to a patient, or, in other words, to measure the dose. They are therefore used in connection with a rheostat and pole-changer. The forms of the two last-mentioned devices have already been patented by me. The rheostat, however, is shown in Fig. 1 at F, and the pole-changer at F'. The milliammeter which I have devised consists of a flattened elliptical hollow coil G, of fine copper wire, within which is suspended a permanent magnet G'. This magnet is of thin flat steel shaped into two arms forming an angle with each other of about ninety degrees. The arms are of equal weight and length and their ends are semicircular. This magnet is pivoted in jeweled bearings g and carries a light needle g' , which plays in front of the scale g^2 . The needle normally stands vertical at zero, and the scale is divided into twenty parts, to the right and to the left, to indicate the direction of current as well as its strength.

o represents a needle-arrester consisting of a pronged wire which may be shoved in or out through the back of the milliammeter-case to inclose or free the needle. The milliammeter is inclosed in a suitable case G^2 , which is hinged at G^3 to the inside of the cover A². It is mounted in such a position that it may be tilted back in a horizontal position, so that it will not interfere with other parts of the apparatus when the cover is closed. The vertical position is of course the working position. When the milliammeter is tilted back,

it is held by a catch g^4 , and when in its raised position it is held by a catch g^4 .

In Fig. 7 I have shown a rod g^5 , which is threaded through a portion of the case supporting the milliammeter. By turning this rod one side of the milliammeter-box will be raised or lowered slightly, for the purpose of leveling the milliammeter and bringing the needle to the zero-point.

g^6 represents a flat spring, to which the bottom board g^9 of the milliammeter-frame is attached. The tendency of this spring is to hold the end of rod g^5 firmly down, thus preventing any jarring or vibration. The catch g^4 is attached to the board g^9 . The meter is provided with switch g^7 , by means of which the current flowing through the magnetizing-coil G and thence to the external circuit may be varied within wide limits and the milliammeter still be in condition to indicate the amount of current flowing upon the same scale, provided as before indicated. I have placed shunt-coils I, of specific resistance, in a separate case in the cover A², and these coils are connected with the switch and with the other circuits in such a manner that by moving the switch g^7 over the contacts g^8 , I am able to vary the current flowing in the coil to either one-tenth or one-hundredth part, respectively, of the full amount of the current. Each division marked on the scale will therefore represent one-tenth or one-hundredth part, respectively, of the current flowing when any shunt-coil is in circuit. Of course the value of the shunt-coils may be varied at will; but those herein presented will give a limit of from one to two thousand millamperes.

My battery when complete with all the attachments and with the fluid in the cells weighs about fifteen and a half pounds. This weight is comparatively light; but if it is necessary to carry the battery in the hands a long distance even this weight will become burdensome, and I have provided a way whereby the apparatus may be divided into two parts, in which case one part may be carried in each hand, thus dividing the weight and rendering it less burdensome to carry. The box or casing is divided into two parts A and A', respectively. The lower part contains the box A³, in which is placed the battery-cells. (Represented in dotted lines in Fig. 4.) The upper part of the box supports the elements D D', &c., of the battery and the other attachments shown in Fig. 1. The upper and lower parts of the battery are secured together by means of spring-catches a and hinges a' . To separate the parts A A' from each other, the spring-catches a are released by pressing the buttons. Then the part A may be tilted back, and, finally, by unlocking the hinges, as will be hereinafter described, the parts are freed and may be entirely removed from each other; but this removal of the parts from each other leaves the upper part without a bottom and the lower part without

a top. I have therefore provided two extra pieces H and J, the one constituting the bottom of the upper part and the other the top of the lower part. The part H is provided 5 with a rubber-cloth-lined pan H', which covers nearly its entire inner surface, and in which may be placed blotting-paper or other absorbent material to catch the drippings from the ends of the electrodes D D'. This 10 part H is provided on its rear edge with two pins h h, which, when it is placed in position, are passed into holes h', (shown in Fig. 2,) formed in the lower edge of the upper part of the box. The front side of the part H is 15 fitted with sockets h², adapted to receive and hold the two spring-catches a on the front side of the box. The part H is then held in its place and forms a neat and substantial bottom for the upper half of the battery-box. 20 The top for the lower half of the box is shown in Fig. 3. It consists of an ordinary rectangular cover of the usual form of box-covers, and it is fitted at the rear with two half-hinges, which are adapted to engage with 25 corresponding half-hinges on the rear side of this portion of the box. The forward edge of this cover is locked down by means of spring-catches a a. Before the cover is placed in position, however, I usually cover the cells 30 with a sealing-board or hydrostat similar to that shown in my Letters Patent, No. 312,650. This completes the covering of the lower half of the box, and by bringing the hand-straps up over the tops and securing them the two 35 parts may be carried one in each hand. The hinges at the back of the box are made so that they may be taken apart. The pin connecting the two parts together is provided at one end with a right-angle offset i. This off- 40 set serves as a handle by means of which the pin may be withdrawn sufficiently to allow the hinges to be taken apart. The entire removal of the pin from the hinge is prevented by the part i coming against the lug i', located 45 between the two hinges. To prevent the accidental removal of the pin, one of the loops through which it passes is left partially open, as illustrated in Fig. 3^a, and the part i runs into this opening and is held there by fric- 50 tion.

Referring now to the manner of raising and lowering the cells for the purpose of putting the battery into or out of operative condition, as before stated, the battery-cells 55 are contained in the box A³, located normally in the lower half of the casing. At central points on the two opposite sides of this box A³ there are attached two semi-cylindrical elongated projections l l'. These projections 60 are in a vertical line with each other and stand in vertical grooves l² formed in the sides of the main casing at opposite points. The projection l at the top of the box A³ is hollow and adapted to receive a spring-catch 65 l³ near its extreme upper edge. Within the projection l is formed a notch l⁴, with which a shoulder l⁵ of the spring-catch l³ is adapted

to engage. The upper projection l may more properly be called a "socket." It, however, at the same time serves as a guide for the box 70 A³. The lower projection l' may or may not be hollow. There are two of these spring-catches l³, one upon each side of the box. They are connected with cords m, which pass up through grooves in the upper half of the 75 main box and over guide-rollers m', mounted near the upper edge of the box. From these rollers the cords lead along the upper edge of the box to other guide-rollers m², near the front edge of the box. From these rollers the 80 cords pass to the opposite ends, respectively, of a rod M, which is about the width of the main box, and when the same is closed the rod occupies a slot or groove M' along the front edge of the box. This rod is provided 85 with a handle M², by means of which it is manipulated. When the cells are to be raised, so as to immerse the battery elements, the rod M is lifted out of the groove M' and carried down over the front of the box, the two cords 90 being led, respectively, through grooves m³ m³. The front of the box is fitted on each side with two vertical ratchets N N, which are adapted to receive at any point the rod M, so as to prevent its outward movement. When 95 the rod is pulled down, the cell-box is lifted and may be supported at any height desired by means of the ratchets N N. The spring-catches l³ l³ are permanently attached to the 100 cords m m, so that when the upper and lower halves of the box are separated the operation is first to tilt the upper half of the box back slightly and then release and remove the spring-catches l³ l³ by pressing the shoulders l⁵ l⁵ from the notches l⁴ l⁴, after which the parts 105 of the case may be separated.

Having thus described my invention, I claim—

1. As a means of coupling the elements of galvanic batteries in series, a supporting plate 110 or board of insulating material having formed in its edge a series of slots, in combination with a series of metallic coupling-clips, each clip having secured to it the positive and negative electrodes of two adjoining separate 115 cells, substantially as described.

2. As a means of supporting the two elements of a galvanic battery, a block of insulating material having secured to it a clip or bracket whose ends stand in parallel planes 120 to two opposite faces of the block and some distance therefrom, the said ends formed with an inward projection, in combination with the two battery elements having grooves at their upper ends, said elements adapted to slide 125 into the spaces between the block and bracket and held in place by the engagement of said projection and grooves.

3. A block for supporting the elements of a battery provided with two sockets—one for each element—in combination with said elements, formed at their upper ends so as to be adjustable laterally, but not vertically, in said 130 sockets, as set forth.

4. A zinc element for galvanic batteries, consisting of a plate having its edges bent to one side to form a kind of trough, in combination with a layer or coating of insulating material filled into said trough, substantially as described.
5. An element for galvanic batteries, consisting of a rectangular plate of zinc having three of its edges bent over to one side to 10 form a kind of trough, and a layer of insulating material confined between the edges of said trough, for the purpose set forth.
6. The combination, with a portable therapeutic galvanic apparatus and its box or case, of a milliammeter hinged to the inside of said box or case and adapted when the cover is in its open horizontal position to be swung into a vertical position, for the purpose described.
7. The combination, with a portable therapeutic galvanic battery and its box or case, of a milliammeter permanently connected therewith and mounted upon an adjustable base, and a screw-rod or equivalent device 25 for adjusting the milliammeter, substantially as described.
8. A box or case for portable galvanic batteries divided into two parts adapted to be separated from each other, one part having attached to it a portion of a galvanic battery and the other part having attached to it the remainder of the battery.
9. A box or case for portable galvanic batteries divided into two parts adapted to be separated from each other, one part having attached to it the elements or electrodes of a galvanic battery and the other part carrying said battery-cells containing the fluid.
10. A box or case for portable galvanic batteries divided into two parts adapted to be separated from each other, one part being hinged to the other by separable hinges.
11. A box or case for galvanic batteries formed in two parts and held together by separable hinges, in combination with top and bottom boards adapted to be adjusted to said parts for protection when the same are separated.
12. A box or case for galvanic batteries formed in two parts and held together by separable hinges, the upper part holding in suspension the elements or electrodes of the battery, in combination with a bottom board constructed to be attached to the lower side of said part when it is separated from the other part of the box to serve as a bottom therefor, said board having formed on its inner side a drip-pan to catch any dripping from the ends of the electrodes, substantially as described.
13. The combination, with a box or case for galvanic batteries formed in two separable parts, of hinges securing the same together, each consisting of two leaves hinged together by a removable pin having an offset, said pin 65 passing through eyes formed on each half of the hinge, one of the eyes being open to permit of the entrance of the offset on the pin, for the purpose set forth.
14. A therapeutic galvanic apparatus consisting of a box or case, the upper part of the same containing the battery elements or electrodes and the lower part a separate box containing the cells of electrolytic fluid, in combination with two cords, one connected 70 with each side of the cell-box and extending vertically upward to the top of the case, where they pass at right angles over guide-rollers, thence over guide-rollers at the front of the box, and finally to the extremities of a 75 handle by means of which the cell-box may be raised, substantially as described.
15. A therapeutic galvanic apparatus consisting of a box or case, the upper part of the same containing the battery elements or 80 electrodes and the lower part a separate box containing the cells of electrolytic fluid, in combination with two cords attached to the cell-box at one end and to a handle at the other end, and ratchets on the front wall of the 85 box or case, with which said handle is adapted to engage, as and for the purpose set forth.
16. The battery box or case formed in two separable parts, the lower part containing a cell-box, in combination with lifting-cords 90 having attached to their extremities spring-catches adapted to engage with the cell-box, as and for the purpose set forth.
17. A portable electric battery contained in a suitable case or box which is separable 95 into two parts, in combination with a sealing-board or hydrostat placed over the top of the cells, substantially as described.
18. The combination, with a portable therapeutic galvanic apparatus and its box or case, 100 of a milliammeter hinged to the inside of said box or case and adapted when the cover is in its open horizontal position to be swung into a vertical position, and means for leveling the milliammeter, substantially as described.
